UNITED STATES PATENT OFFICE.

MANUEL A. VINAS, OF NEW YORK, N. Y.

HANDLELESS CLOCK.

Application filed August 29, 1925, Serial No. 53,268, and in the Dominican Republic April 18, 1925.

This invention relates to clocks and more especially to handleless clocks.

It is the purpose of this invention to provide means whereby clockwork mechanism of the hand indicator type may be readily adapted to provide dial type indications.

It is a special purpose of this invention to provide mechanism for dial clocks which will have few parts, be simple and cheap to build and adjust, and which will be sufficiently rugged to withstand ordinary use and abuse.

The ordinary hand type of clock has entered into such wide use and its manufacture has been so standardized that even those skilled in the art appear inclined to neglect the dial type of clock indicator which nevertheless has many advantages such as ease of reading and the practicability of making such reading directly in terms and symbols identical with those commonly used in timetables and the like. In the dial type, or so called handleless type, clock it is usual to shield all but the correct insignia for a given time from view and this feature, impractical in the hand type, manifestly greatly decreases the liability of error in reading and renders any one minute exactly as readable as any other whereas in the hand type indications at the hour, half hour, and quarter hours, are many times easier to see than any other indications while on small faced clocks minute indications are often barely legible a few inches distant. However in the past the dial type clocks have required works which were of special form and which involved the use of parts not in any way standard to the clockmaking industry so that high cost and difficulty of construction have rendered it practically impossible to realize the benefits of dial time indication. The herein disclosed invention will be seen to provide means for producing such dial indicator clocks without the use of special parts and in such manner that the larger portion of the mechanism employed may be identical with that used for the hand type clocks at the present time, thus removing the hereinbefore set forth difficulties and providing all of the advantages delineated.

A further object of the invention lies in the supply of a unitary mechanism for converting rotary hand shaft movements into periodic dial indicator movements and in providing means whereby such unitary

mechanism may be attached to the clockwork supplied for, and standard to, hand type clocks.

This invention also contemplates the provision of means whereby the hand type 60 clockwork movement may be accelerated at periods during which the dials are being turned from one indication to the next.

Certain other objects and improvements supplied by this invention will become evident as the description proceeds and in referring to the drawings, in which:

Fig. 1 is a front elevation of a dial or handleless type clock embodying my invention.

Fig. 2 is an elevation, taken from the front, of the dials employed to carry the time indicating insignia. The clock face is here removed and details of the operating mechanism omitted.

Fig. 3 shows to enlarged scale the dial operating mechanism and is taken in elevation, the position of the dials being indicated by dotted lines.

Fig. 4 shows in elevation a portion of the 30 gearing used in a standard hand type clockwork and illustrates an alteration therein especially adapted to further the operation of this invention.

Fig. 5 illustrates a detail of the hour indicating dial drive.

Fig. 6 is a detail view in section on line 6—6, Fig. 5.

The indicator mechanism consists of three dials; the units minutes dial, the tens minutes dial, and the hour dial; the units minutes dial bears indicating emblems, in this case Arabic numerals from 0 to 10 arranged around its center and adjacent its periphery. The tens minutes dial bears two series of 30 numerals reading from zero to five inclusive arranged similarly to those on the units minutes dial. The hour dial bears a single series of numerals similarly arranged to those on the units minutes dial but reading 100 from 1 to 12. It being understood of course that for other time systems, such as the Greenwich for example, other numbers of numerals or different forms of emblems may be equally well used. For the operation of 105 the dials suitable gearing, having intermittent movements therein for periodically revolving the dials through an arc equal to one emblem, is provided and supplementary to such gearing a unitary support attachable 110

to the framework of a hand type clockwork in such manner that power may be derived therefrom is furnished. The clock face supplied with three windows revealing only a single numeral on each dial completes the embodiment with the exception of a single mutilated gear which is preferably inserted in the clockwork train between the hour hand shaft and the clockwork governor or balance wheel.

More specifically referring to the drawings:

The clock face 10 mounted in a suitable case 12 and covered by a crystal held in the hinged bezel 14, is provided with an hour indication opening or window 16, with a units minutes indication window 17 and with a tens minutes window 18. It is also usual to provide such faces with winding key openings 19, with a second hand dial 20 and with various other adjustments and openings therefor as those skilled in the art will understand.

Through window 16, and more plainly in Fig. 2, may be seen the hour dial 22 consisting of a flat disc journaled on hollow arbor 24, bearing the numerals 1 to 12 on its upper face, provided with twelve downwardly turned driving lugs 26 and having secured to its under surface a locking wheel 28 whose teeth 29 engage a locking spring 30 and assure that this dial always comes to rest with one of the numerals in correct registry with window 16.

At window 18 and in Figs. 2, 3, 5 and 6 is visible the tens minutes dial 32 consisting of a flat disc somewhat smaller in diameter than disc 22, journaled on arbor 33, bearing two series of six numerals (each series reading from 0 to 5 inclusive) on its upper face, provided with two hour dial drive fingers 34 and 35 secured to its periphery, and having secured to its under surface its drive gear 37 whose teeth 38 also engage a locking spring 40 whose purpose is similar to that of spring 30 causing the numerals to correctly register with window 18.

The units minutes dial 42, seen at window 17 Fig. 1 and in Figs. 2 and 3, is a flat disc preferably of the same diameter as discs 32, journaled on arbor 43, bearing a single series of 10 numerals (reading from 0 to 9 inclusive) on its upper surface, and having secured to its under surface a drive gear 45 whose teeth 41 also engage locking spring 50 and a tens minutes dial driving pinion 46. Pinion 46 engages and drives gear 47 journaling on arbor 47^a. Gear 47 in turn drives a pinion 48 secured to the top of which, and revolving with the pinion, is a single tooth gear 49 engaging the tens minutes dial drive gear 37 once each revolution of gear 49. Pinion 48 and gear 49 journal as a unit on arbor 49^a. This gear train serves to turn the tens minutes dial the space of one

numeral for each complete revolution of the units minutes dial.

Units minutes dial drive gear 45 is actuated by the engagement of teeth 52 of gear wheel 54 which journals on arbor 54^a and to which is secured pinion 55 engaged with and driven by main drive gear 56. Gear 56 directly, or through an adapter, engages the hour hand shaft 60 which projects from the front frame of the usual hand type clockwork.

The particular type, and the details of the clockwork proper are immaterial to this invention, such clockworks are well known to those skilled in the art and need not be neither shown nor described herein, it being understood that these devices usually consist of a power element, such as a spring or the like, and a governor for the power element, such as a balance wheel or the like. Suitable gearing connects these and the hour, minute, and second hands. With the minute hand gearing this invention has no concern, this may be removed or not as desired. Fig. 4 serves to show a portion of one form of such gearing as is commonly employed between the hour hand shaft and the balance wheel or governor. Gear 62 secured to the hour hand shaft 60 drives pinion 63 rotating shaft 64 and therethrough gear 65 driving pinion 70, shaft 71 and the gear 72. Through pinion 74 escape wheel 75 pallets 76 lever 77 and pin 78 oscillatory motion is applied to balance wheel 80. A suitable spring on the balance wheel shaft generally completes the clockwork governor mechanism which may be said to consist of escape wheel 75, pallets 76, lever 77, pin 78 and balance wheel 80 in particular.

At a suitable point in the governor drive gearing the ordinary regular toothed gear is removed and a mutilated gear 65 substituted. Gear 65 is provided with five groups of eight teeth each (see 66 Fig. 4) regularly spaced around the gear circumference and between these five groups five spaces without teeth are provided. Thus in operation the governor mechanism is disengaged from the clockwork power mechanism whenever the end of a tooth group is reached and pinion 71 is reengaged when the beginning of the next tooth group reaches it. During the period of governor disengagement the clockwork power mechanism is free to speed up and it is the purpose of this mutilated gear to permit such speeding up when the indicator dials are moving, thus accelerating the rate of change and reducing the time for appearance of the next numeral to a minimum.

Preferably the entire dial drive mechanism and dials are supported through suitable journals or arbors, such as journal 24 and arbors, 54^a, 43, 47^a, 49^a, and 33, engaging a single support frame 90 which may

also mount suitable posts, 30^a, 40^a and 50^a holding the locking springs 30, 40 and 50 respectively. This frame 90 thus serves as a means for assembling the dial mechanism 5 as a unit and for making all necessary adjustments to such mechanism before applying the same to a clockwork. Application is thus reduced to applying gear 56 to hour hand shaft 60 (which passes through an 10 opening in frame 90), and clamping frame 90 to the clockwork frame 92 by such means as the screws 94, gear 65 being inserted in the clockwork if desired.

In operation the clockwork power mechanism 15 drives hour hand shaft 60 rotating gear 56 and therethru pinion 55 and toothed wheel 54. Periodically teeth 52 on wheel 54 engage a tooth 41 on gear 45 and turn dial 42 (the units minutes dial) the space 20 of one numeral causing spring 50 to be forced over one tooth 41 and in snapping back to force dial 42 into correct registry with window 17. In rotation dial 42 carries with it pinion 46 driving single tooth gear 49 through gear 47 and pinion 48. Once each revolution of dial 42 and of gear 49, a tooth 38 of gear 37 is engaged and dial 32 turned the space of one numeral; 25 spring 40 snapping over a tooth 38 and forcing the dial to come to rest with its next numeral in correct registry with window 18. Dial 32 having two series of numerals thereon (when standard time system is employed) makes a complete revolution 30 once in two hours and a half revolution each hour. Upon dial 32 and projecting from its periphery are the fingers 34 and 35 so spaced that once each half revolution of dial 32 a lug 26 of dial 22 is engaged (see Figs. 40 5 and 6) and the hour dial turned the space of one numeral; spring 30 being forced over a tooth 29 on gear 28 and in turn forcing dial 22 to come to rest with its next numeral in correct registry with window 16.

45 In such cases as a second hand is required shaft 71, or other suitable correctly timed shaft, is projected through hollow journal

24 and through the clock face so that second hand 71^b may be affixed.

Setting and winding of this dial clock 50 may be accomplished by operation of the controls originally provided and these controls may be rendered accessible from the clock face through openings 19 and the like after the manner well known to the art 55 when desired.

Manifestly many changes and modifications in the embodiment of this invention, and particularly those changes necessary to adapt the mechanism for the indication of 60 other time systems, are well within the scope of this invention and the spirit of the appended claims.

I claim—

1. In dial indicator mechanism for converting clocks of the hand type, a support member engageable with the clockwork frame, a tens minutes dial, a units minutes dial, an hours dial, dial drive gearing connecting said dials and timing relative movements thereof, said drive gearing including intermittently engaging gears and a main drive gear engaging the hour hand shaft of the hand clockwork mechanism, said support member provided with journal and arbor 75 bearings whereon said dials and dial drive gearing may be assembled and applied as a unit to said clockwork to convert the same to a dial indicator clock.

2. In time piece dial indicator mechanism, a gear engaging the timepiece hour hand shaft, a spaced tooth gear driven by the first said gear, a gear secured to a minutes indicator dial shaft and intermittently turned by engagement of the said 80 spaced teeth, a single-toothed gear actuated from said dial shaft and intermittently engaging a gear on a second minutes indicator dial shaft, an hour indicator dial having spaced lugs thereon, and fingers on said 85 second minutes dial intermittently engaging the lugs on said hour dial to turn the same.

Signed at New York 27th August, 1925.
MANUEL A. VINAS.
